US0D1033042S

(12) **United States Design Patent** (10) **Patent No.:** **US D1,033,042 S**
(45) **Date of Patent:** **** Jul. 2, 2024**

(54) **SHOE**

(71) Applicant: **NIKE, Inc.**, Beaverton, OR (US)

(72) Inventors: **Colin Behr**, Portland, OR (US);
Benjamin Nethongkome, Beaverton, OR (US); **Paul Savovici**, Portland, OR (US)

(73) Assignee: **NIKE, Inc.**, Beaverton, OR (US)

(**) Term: **15 Years**

(21) Appl. No.: **29/895,588**

(22) Filed: **Jun. 23, 2023**

(51) LOC (14) Cl. **02-04**

(52) U.S. Cl.

(57) **CLAIM**

The ornamental design for a shoe, as shown and described.

DESCRIPTION

FIG. 1 is a side view of a shoe showing our new design;

FIG. 2 is a rear perspective view thereof;

FIG. 3 is a rear view thereof;

FIG. 4 is an opposite side rear perspective view thereof; and,
FIG. 5 is an opposite side view thereof.

The broken lines depicting the remainder of the shoe form
no part of the claimed design.

1 Claim, 5 Drawing Sheets
